UNITED STATES PATENT OFFICE.

DANIEL A. MOONEY, OF PHILADELPHIA, AND OTTO JAEGER, OF ELKINS PARK, PENNSYLVANIA, ASSIGNORS, BY DIRECT AND MESNE ASSIGNMENTS, TO WALTER WRIGHT, OF JENKINTOWN, PENNSYLVANIA.

CLOTHES WRINGER.

Application filed September 14, 1927. Serial No. 219,393.

Our invention relates to improvements in clothes wringers and particularly power-driven wringers, and also wringers in which the press rolls may be rotated in either direction.

The object of our invention is to provide movable feeding tables for feeding the clothes between the press rolls to eliminate the danger of the fingers of the operator being drawn between the rolls, and to mount the feeding tables in a novel manner in which said tables will be normally positioned at rest a short distance from the rolls ready to receive the clothes and to be operable to feed the clothes placed thereon into the bite of the rolls; a further object of our invention is to provide a drain board with means for automatically tilting the same when the tables are operated, so that the board will drain the water toward the side of the table being operated and into a receptacle located under the table which is being operated; a still further object of our invention is to provide an indicating means upon one, or both, of the press rolls for showing the operator when the rolls are in motion and also showing the direction of rotation of said rolls, for reducing the danger of the operator being injured by the rolls. Accidents have occurred by the operator not being able to see that the press rolls are in motion, as devices of this kind are usually used in poorly lighted rooms and driven by electric motors which prevent the sound of the clothes wringer being heard above the sound of the motor. These, together with various other novel features of construction and arrangement of the parts, which will be more fully hereinafter described and claimed, constitute our invention.

Referring to the accompanying drawings, Figure 1 is a front elevation of our improved wringer; Figure 2 is an end view of the wringer, partly in section, showing the feeding tables in full lines in the normal, or inoperative position, and in dotted lines in the operative position; and Figure 3 is a vertical sectional view as on line 3-3, Figure 1.

In the drawings, in which like reference characters refer to like parts, 5 represents a frame having end bearings 6 and 7 in which are mounted the press rolls 10 and 12. The frame 5 is mounted upon a rotatable standard 14 having a housing 15 in which is located the

gear mechanism which may be turned in either direction for rotating the rolls in either direction. Our invention, hereinafter described, may be embodied in any other form of power wringers, as various other forms are now in general use.

The press rolls 10 and 12 of wringers are generally provided with a flexible covering, such as rubber. In carrying out our invention the press roll 10 is provided with indicating marks such as stripes 16 and 17 formed of distinguishing colors, as shown in Figures 1 and 3. The stripes 16 and 17 may be formed upon the surface of the roll, or the roll may be formed of materials of different colors. Said marks may be of various shapes and arranged on one or both rolls, for the purpose of better showing when the rolls are in motion and also the direction of rotation of the rolls, thereby reducing the possibility of the operator's fingers being caught in the rolls.

Feeding tables 18 and 20 are provided for feeding the clothes into the bite of the press rolls 10 and 12. Said tables 18 and 20 comprise each a U-shaped member consisting of the top portion 21 extending longitudinally of said rolls and end arms 22 and 23, carrying said portion 21, and having their lower ends 25 curved inwardly towards the central vertical plane extending lengthwise of the frame 5. The arms 22 and 23 are pivoted, by means of pins 26, to extension brackets 27 and 28, mounted upon the end members 6 and 7 of the frame 5. Said pivot pins 26 are located adjacent to the longitudinal center of the frame 5, below the press rolls, so that the center of gravity of the tables will be outside of the frame 5, thus normally positioning the tables in the inoperative position away from the press rolls, as shown in full lines, Figure 2.

The tables 18 and 20 are provided with shoulders 30, located at the ends of the top plate 21 of the tables, which shoulders strike against the front vertical surface of the frame 5 and limit the movement of the tables towards the press rolls. Said top plate 21 of each table has an extension portion 32, which projects from the line of the shoulders 30 and forms an edge on the table for forcing the clothes between the bite of the rolls when the tables are moved towards the rolls. Said shoulders 30 prevent the extension portion 32 from touching the press rolls. Said portion

32 occupies the full length of the space between the end bearings 6 and 7 of the frame 5, thus forming a guard which will prevent the fingers of the operator coming in contact 5 with both press rolls simultaneously. If the fingers are caught between the table and the upper press roll, the fingers can be pulled out against the friction exerted by one roll and the table; the latter, being free to move 10 away from the rolls, will assist the fingers in being drawn out of danger and free of the upper roll.

A drain board 35 is supported upon a pivot shaft 36, having its ends rotatably mounted 15 in the end bearings 6 and 7. An arm 37 is secured upon the shaft 36 and is adapted to be acted upon by projections 39 formed upon the arms 22 of the tables. Said projections 39 are adapted to take against the arm 37 and 20 tilt the board 35 into a position which will drain the water toward the table which is operated.

Figure 3 shows the board 35 moved into an operative position by the movement of the 25 table 20 toward the rolls. Said table 20 may drop back to its normal position shown in full lines, Figure 2, and the drain board will not change its position until it is shifted by a movement of the table 18, which will move 30 the board 35 into the position shown in full lines in Figure 2, ready to drain the water toward the table 18, which is in operation.

The projections 39 upon the arms of the feeding tables are provided with shoulders, or hooks, 40, which interlock with the bottom 35 edge of the cover plates 41 of the frame 5, thus forming stops for limiting the movement of the tables 18 and 20 away from the rolls and holding the tables in a normal position, as shown in full lines, Figure 2, ready 40 to receive the clothes to be passed between the press rolls by manually moving either of the feeding tables into the positions shown in dotted lines, Figure 2, so that the extension portions 32 of the tables will force the clothes 45 into the bite of the rolls, thus avoiding the necessity of the operator's fingers being placed near the press rolls. The drain board will be automatically shifted into the operative position relatively to the feeding table 50 which is operated. The color stripes upon one of the press rolls will attract the eye of the operator as a danger warning when the rolls are in operation.

55 Various changes may be made in the details of construction and arrangement of the parts without departing from our invention.

We claim:—

1. A clothes wringer comprising a frame, press rolls rotatably mounted in said frame, 60 a feeding table movably mounted upon said frame and movable from a normal position away from said rolls to a position close to said rolls for feeding clothes between said rolls, a drain board mounted in said frame below said rolls, and means for setting the drain board in an operative position with relation to said table when the table is moved from its normal position.

2. A clothes wringer comprising a frame, 70 press rolls rotatably mounted in said frame, a drain board mounted in said frame below said rolls, feeding tables mounted upon said frame at opposite sides of said rolls, said 75 tables being movable independently of each other to and from said rolls for feeding clothes between said rolls, and means upon each table for tilting said drain board into a position for draining toward the side of said rolls occupied by the table which is in 80 operation.

3. A clothes wringer comprising a frame, press rolls rotatably mounted in said frame, a drain board pivotally mounted in said frame, an arm upon said drain board, feeding 85 tables mounted upon said frame at opposite sides of said rolls, said tables being movable independently of each other from an inoperative position towards said rolls for feeding clothes between said rolls, and a part upon 90 each table adapted to engage said arm and move said drain board into an operative position when either table is moved towards said rolls.

4. A clothes wringer comprising a frame, 95 press rolls rotatably mounted in said frame, a drain board pivotally mounted in said frame, an arm upon said drain board, tables positioned at opposite sides of said rolls, depending arms at opposite ends of the tables 100 for supporting the same, said arms having inwardly curved lower portions, bearing upon said frame in which the lower portions of the arms are pivoted, a projection upon said arms adapted to engage the arm upon the 105 drain board for tilting the latter, a part upon said frame forming a stop, and a part upon said arm adapted to engage said stop when the table is moved away from the rolls.

In testimony whereof we affix our signatures.
